US010625137B2

(12) **United States Patent**
Dalebout et al.

(10) **Patent No.:** **US 10,625,137 B2**
(45) **Date of Patent:** ***Apr. 21, 2020**

(54) **COORDINATED DISPLAYS IN AN EXERCISE DEVICE**

(71) Applicant: **ICON Health & Fitness, Inc.**, Logan, UT (US)

(72) Inventors: **William T. Dalebout**, North Logan, UT (US); **Gordon Cutler**, Providence, UT (US)

(73) Assignee: **ICON Health & Fitness, Inc.**, Logan, UT (US)

(*) Notice: Subject to any disclaimer, the term of this patent is extended or adjusted under 35 U.S.C. 154(b) by 273 days.

This patent is subject to a terminal disclaimer.

(21) Appl. No.: **15/460,946**

(22) Filed: **Mar. 16, 2017**

(65) **Prior Publication Data**

US 2017/0266533 A1 Sep. 21, 2017

COORDINATED DISPLAYS IN AN EXERCISE DEVICE

RELATED APPLICATIONS

This application claims priority to U.S. Patent Application Ser. No. 62/310,343 titled "Coordinated Displays in An Exercise Device" and filed on 18 Mar. 2016, which application is herein incorporated by reference for all that it discloses.

BACKGROUND

Aerobic exercise is a popular form of exercise that improves one's cardiovascular health by reducing blood pressure and providing other benefits to the human body. Aerobic exercise generally involves low intensity physical exertion over a long duration of time. Typically, the human body can adequately supply enough oxygen to meet the body's demands at the intensity levels involved with aerobic exercise. Popular forms of aerobic exercise include running, jogging, swimming, and cycling among others activities. In contrast, anaerobic exercise typically involves high intensity exercises over a short duration of time. Popular forms of anaerobic exercise include strength training and short distance running.

Many choose to perform aerobic exercises indoors, such as in a gym or their home. Often, a user uses an aerobic exercise machine to have an aerobic workout indoors. One type of aerobic exercise machine is a treadmill, which is a machine that has a running deck attached to a support frame. The running deck can support the weight of a person using the machine. The running deck incorporates a tread belt that is driven by a motor. A user can run or walk in place on the tread belt by running or walking at the tread belt's speed. The speed and other operations of the treadmill are generally controlled through a control module that is also attached to the support frame and within a convenient reach of the user. The control module can include a display, buttons for increasing or decreasing a speed of the conveyor belt, controls for adjusting a tilt angle of the running deck, or other controls. Other popular exercise machines that allow a user to perform aerobic exercises indoors include elliptical machines, rowing machines, stepper machines, and stationary bikes to name a few.

One type of treadmill is disclosed in U.S. Patent Publication No. 2009/0209393 issued to Bradley A. Crater. In this reference, a simulated display of a treadmill's console is described. According to one embodiment, the console displays a visual representation of the course over which the user is running. By way of example and not limitation, the course may be displayed with video footage that corresponds to the user's location on the course, by using still pictures, or by using computer-generated simulations of the course. For example, a video display of the course could assist a marathon runner who is preparing for the Boston Marathon. By seeing a visual representation of the course, a runner could identify landmarks and aid stations that would assist him in feeling comfortable in running the actual race being simulated at a future date.

SUMMARY

In one embodiment, an exercise device includes a frame, an upright portion of the frame, a movable element connected to the frame and movable in the performance of an

2

exercise, a first display connected to the upright portion of the frame, and a second display connected to the frame.

The second display may be adjacent to the movable element.

5 The second display may be below at least a portion of the movable element.

The exercise device may further include an exercise deck where the exercise deck includes a first pulley connected to a front portion of the deck, a second pulley connected to a 10 rear portion of the deck, and a tread belt surrounding the first pulley and the second pulley. The tread belt may surround at least a portion of the second display.

The images depicted in the first display and the second display may be coordinated.

15 The exercise device may include a video splitter that outputs a first video stream to the first display and a second video stream to the second display.

The first video stream and the second video stream may be identical.

20 The first video stream may contain at least some data that does not overlap with the data in the second video stream.

The first video stream may contain overlapping data with the second stream, and the overlapping data is delayed from presentation in the second display from when the overlapping 25 data is displayed in the first display.

The overlapping data may depict a scene and where the delay causes the effect of having the scene appear to transfer from the first display to the second display.

The frame may include a first rail, a first track defined in 30 the first rail, a second rail space apart at a distance from the first rail, a second track defined in the second rail, a slatted running track. The slatted running track may include multiple slats and multiple pins holding the multiple slats together to form the slatted running track. A first end of the 35 multiple pins may be inserted into and follows the first track, and a second end of the multiple pins may be inserted into and follows the second track.

The movable element may be a foot pedal.

The exercise device may be a rowing machine.

The exercise device may be a stationary bicycle.

40 The display may be covered with a transparent plastic film.

In one embodiment, an exercise device includes an 45 upright structure, a first display connected to the upright structure, and an exercise deck connected to the upright structure. The exercise deck includes a first pulley connected to a front portion of the exercise deck, a second pulley connected to a rear portion of the exercise deck, a tread belt surrounding the first pulley and the second pulley, and a second display is incorporated into the deck and is adjacent to or below a portion of the tread belt. Images depicted in the 50 first display and the second display are coordinated.

The exercise device may include a video splitter that outputs a first video stream to the first display and a second 55 video stream to the second display.

The first video stream may contain overlapping data with the second stream, and the overlapping data is delayed from presentation in the second display from when the overlapping data is displayed in the first display.

60 The overlapping data may depict a scene and where the delay causes the effect of having the scene appear to transfer from the first display to the second display.

In one embodiment, an exercise device includes an upright structure, a first display connected to the upright structure, and an exercise deck connected to the upright structure. The exercise deck includes a first pulley connected to a front portion of the exercise deck, a second pulley

connected to a rear portion of the exercise deck, a tread belt surrounding the first pulley and the second pulley, and a second display is surrounded by the tread belt. The exercise device further includes a processor and memory where the memory including programmed instructions that, when executed, cause the processor to output a first video stream to the first display, output a second video stream to the second display, and delay overlapping data between the first video stream and the second video stream from presentation in the second display from when the overlapping data is presented in the first display to cause the effect of having the scene appear to transfer from the first display to the second display.

BRIEF DESCRIPTION OF THE DRAWINGS

The accompanying drawings illustrate various embodiments of the present apparatus and are a part of the specification. The illustrated embodiments are merely examples of the present apparatus and do not limit the scope thereof.

FIG. 1 illustrates a perspective view of an example of a treadmill in accordance with the present disclosure.

FIG. 2 illustrates a perspective view of an example of a treadmill in accordance with the present disclosure.

FIG. 3 illustrates a perspective view of an example of a treadmill in accordance with the present disclosure.

FIG. 4 illustrates a perspective view of an example of a treadmill in accordance with the present disclosure.

FIG. 5 illustrates a block diagram of an example of a coordinating system in accordance with the present disclosure.

FIG. 6 illustrates a top view of an example of a display incorporated into an elliptical trainer in accordance with the present disclosure.

FIG. 7 illustrates a top view of an example of a display incorporated into a stationary bicycle in accordance with the present disclosure.

FIG. 8 illustrates a top view of an example of a display incorporated into a rowing machine in accordance with the present disclosure.

FIG. 9 illustrates a perspective view of an example of a treadmill in accordance with the present disclosure.

FIG. 10 illustrates a perspective view of an example of a treadmill in accordance with the present disclosure.

Throughout the drawings, identical reference numbers designate similar, but not necessarily identical, elements.

DETAILED DESCRIPTION

For purposes of this disclosure, the term "aligned" means parallel, substantially parallel, or forming an angle of less than 35.0 degrees. For purposes of this disclosure, the term "transverse" means perpendicular, substantially perpendicular, or forming an angle between 55.0 and 125.0 degrees. Also, for purposes of this disclosure, the term "length" means the longest dimension of an object. Also, for purposes of this disclosure, the term "width" means the dimension of an object from side to side. For the purposes of this disclosure, the term "above" generally means superjacent, substantially superjacent, or higher than another object although not directly overlying the object. Further, for purposes of this disclosure, the term "mechanical communication" generally refers to components being in direct physical contact with each other or being in indirect physical contact with each other where movement of one component affect the position of the other.

Particularly, with reference to the figures, FIG. 1 illustrates a perspective view of an example of a treadmill 100. In this example, the treadmill 100 includes an exercise deck 102 and an upright structure 104. The upright structure 104 includes a first post 106 and a second post 108. The first post 106 and the second post 108 support a console 110. A display 112 is incorporated into the console 110.

The exercise deck 102 includes a platform. A first pulley (not shown) is incorporated into a front portion 114 of the exercise deck 102, and a second pulley (not shown) is connected to a rear portion 116 of the exercise deck 102 opposite the first pulley. A tread belt 118 surrounds the first pulley and the second pulley. In the example of FIG. 1, the first and second pulleys are obscured from view underneath portions of a top surface of the platform. The platform may have a length along its longest dimension and a width that is transverse the length. The platform's edges along both the width and the length have a wide section on which the user can stand.

The platform also includes a display screen 120 integrated into the platform. This display screen 120 may be used to display information associated with the workout, with the user, with local news, with other types of information, or combinations thereof. In some cases, the deck display screen is controlled through the console, a remote device, or an input mechanism incorporated into the deck. The display screen 120 may also be surrounded by the tread belt 118. In some cases, the display screen 120 is wider than the tread belt 118. In this situation, the display screen 120 includes a first portion 122 adjacent a first edge 124 of the tread belt 118 that is unobscured from view, and a second portion 126 adjacent a first edge 128 of the tread belt 118 that is unobscured from view. In this example, the display screen 120 spans the inside surface of the tread belt 118.

FIG. 2 depicts an example of treadmill 200 with a console display 202 and a deck display 204. In this example, a tread belt is removed for illustrative purposes. The console display 202 and the deck display 204 may collectively operate in an extended view that depicts different portions of the same scenery. In this example, the same trail is depicted in the console display and the deck display, but the console display 202 presents a first portion of the trail and the deck display 204 presents a second portion of the same trail.

FIG. 3 depicts an example of a treadmill 300 as the user progresses along the trail depicted in the console display 302 and the deck display 304. For example, the rock (depicted in FIG. 2, 206), which was previously presented in the console display 302 is now presented in the deck display 304.

FIG. 4 depicts an example where the same content presented in the console display 400 is also presented in the deck display 402.

FIG. 5 depicts an example of a coordinating system 500. In this example, the coordinating system 500 includes processing resources 502 and memory resources 504. The memory resources 504 may cause the processing resources 502 to carry out functions programmed in the memory resources 504. In this example, the memory resources 504 include a first display timer 506, a second display timer 508, a transition synchronizer 510, and a video library 512.

The processing resources 502 may be in communication with I/O resources 514, which may include a receiver, a transmitter 516, a transceiver, another type of communication device, or combinations thereof. Further, the processing resources 502 may be in communication with the first display 518, the second display 520, and a video splitter 522, another type of device, or combinations thereof.

FIG. 6 depicts an example of an elliptical trainer 600. The elliptical trainer 600 includes a frame 602 attached to a base 604. The frame 602 includes a first post 608 and a second post 610. An upright console 612 is connected to the first and second posts 608, 610. The first frame post 608 incorporates a first flywheel 614, and the second frame post 610 incorporates a second flywheel 616. The first flywheel 614 is connected to a first pedal assembly 618 through a crank assembly 620, and the second flywheel 616 is connected to a second pedal assembly 622 through the crank assembly 620.

The crank assembly 620 includes a first crank arm connected to the first flywheel 614 and a second crank arm connected to the second flywheel 616. Each of the first crank arm and the second crank arm include a roller that supports the weight of the pedal assemblies 618, 622 and a user standing thereon.

Each of the first pedal assembly 618 and the second pedal assembly 622 include a pedal beam, and a pedal is connected to the pedal beam. The pedal may include a gripping surface to grip a user's shoe as a user executes an exercise with the elliptical trainer 600. The pedal may be bolted or otherwise fastened to the pedal beam.

A front end of the pedal beam of the first pedal assembly 618 is connected to a first arm lever 652 that connects to the frame 602 at a first pivot connection. The first pivot connection is also attached to a first handle section 656 which is accessible to the user as the user is performing an exercise with the exercise machine 600. The pedal beam of the second pedal assembly 622 is connected to a second arm lever 660 that connects to the frame 602 at a second pivot connection. The second pivot connection is also attached to a second handle section 664 which is also accessible to the user as the user is performing an exercise with the elliptical trainer 600. As the pedal beams move, the first and second handle sections 656, 664 move accordingly.

The console 612 may contain a display and controls. The controls may allow the user to specify a resistance level to be applied by the resistance mechanism, such as the first and second flywheels 614, 616. In some examples, the controls may also be used to control other operating parameters of the exercise machine, such as incline, side to side tilt, resistance, speaker volume, programmed exercise routines, other parameters, or combinations thereof. The display may show selected parameters to the user. Additionally, the display may be capable of presenting the user's physiological parameters, timers, clocks, scenery, routes, other types of information, or combinations thereof.

Further, a display 670 is incorporated into the base 604. In this example, the display 670 is below the pedals assemblies 618, 622, the crank assembly 620, and the flywheels 614, 616. As the user exercises on the elliptical trainer 600, the user can view portions of simulated scenery and/or other types of information presented in the base's display 670. While this example has been described with two display screens, in other examples, the elliptical trainer may include just a single display screen that is incorporated into the exercise machine's base, located beneath the crank assembly, and/or located beneath the upright portion.

FIG. 7 depicts an example of a stationary bicycle 700. In this example, the stationary bicycle 700 includes a frame 702 and a crank assembly 704 attached to the frame 702. A seat 706 is also attached to the frame 702 and positioned above the crank assembly 704. The stationary bicycle 700 also includes an upright portion 708, and a console 710 with a first display 712 is attached to the upright portion 708.

A second display 714 is positioned underneath at least a portion of the frame 702. In this example, the second display 714 is attached below the crank assembly 704. While this example has been described with just two displays, in some examples, the stationary bicycle includes just a single display located beneath the crank assembly and/or located beneath an upright portion of the stationary bicycle.

FIG. 8 depicts an example of a rowing machine 800. In this example, the rowing machine 800 includes a main frame member 802 supported by rear supports 804 and a front cross member 806. A flywheel 808 is incorporated into a front portion of the rowing machine 800. A pull cable 810 is connected to the flywheel 808 at a first cable end, and a handle 812 is connected to the pull cable 810 at a second cable end. A seat 814 is slidably attached to the main frame member 802.

A first display screen 816 is attached to a console 818 of the rowing machine 800. A second display screen 820 is attached to the rowing machine 800 beneath the main frame member 802. In this example, the second display screen 820 is located beneath the resistance mechanism (i.e. the flywheel). While this example is depicted with two displays, in other examples, the rowing machine includes a single display located beneath the main frame member 802.

FIG. 9 depicts an example of a treadmill 900 with a console display 902 having an inwardly curved screen 904. In this example, the scenery depicted in the console display 902 may create a more realistic feel that the user is in the simulated environment.

FIG. 10 depicts an example of a treadmill 1000 with a slatted running track 1002. Also, in this example, the treadmill 1000 includes a console screen 1004 with multiple displays. A first display 1006 depicts scenery. In this example, the other displays 1008, 1010, 1012, 1014, 1016, 1018 each depict different content. At least some of the content in one of the other displays 1008, 1010, 1012, 1014, 1016, 1018 is coordinated with the content in the first display 1006. In this example, the console screen 1004 also includes an inwardly curved surface.

General Description

In general, the invention disclosed herein may provide a user with a treadmill that has several advantages over conventional treadmills. The treadmill may include a running deck that has first pulley in a front portion of a platform and a second pulley incorporated into a rear portion of the platform. A tread belt may surround the first and second pulley. A motor can be attached to either the first or the second pulley so that as the motor rotates its shaft, the connected pulley rotates with the motor causing the tread belt to move.

The platform may have a length along its longest dimension and a width that is transverse the length. The width of the tread belt may span just a portion of the treadmill deck's platform. In this circumstance, the deck is wider than the tread belt. Thus, a first portion of the deck may extend past a first side of the tread belt, and a second portion of the deck may extend past a second side of the tread belt.

In some examples, the treadmill may include an upright structure. The deck may be connected to the upright structure so that the upright structure is oriented transversely to the deck. An incline mechanism may be incorporated into the treadmill so that the deck can change its incline orientation with respect to the upright structure. In some cases, the deck can be oriented at an inclined orientation, a

declined orientation, or a neutral orientation. Further, in some instances, the treadmill deck has the capability of tilting from side to side.

A console may be connected to the upright structure. The console may include a display, an input mechanism, a cooling mechanism, a retention area for holding an object (e.g. mobile device, book, water bottle, etc.,), or combinations thereof. The console's display may present various types of information to the user.

The input mechanism provides the user means to communicate with the treadmill. For instance, the user may select a tread belt speed, a pre-programmed workout, a climate setting, an incline orientation, a tilt orientation, an entertainment setting, and so forth, with the input mechanisms. The input mechanisms may include a touch screen, a push button, a dial, a lever, a microphone, another type of input mechanism, or combinations thereof.

For example, the console may present physiological information about the user, like the user's heart rate. Also, the console may also depict the type of programmed workout selected, the tread belt's speed, the distance traveled by the user, another type of parameter, or combinations thereof. In some cases, the console's display may depict scenery to provide a feel that the user is exercising outdoors. In some cases, the orientation of the deck's platform may be synched with the scenery so that the deck mimics the terrain depicted in the display. For example, the platform may be inclined when the display depicts that the path is going uphill, or the platform may be declined when the display depicts that the path is going downhill.

In some embodiments of the invention, a second display is incorporated into the deck's platform. This deck display may be positioned under the tread belt, adjacent to the tread belt, to the side of the tread belt, forward of the tread belt, rearward of the tread belt, or combinations thereof.

The second display may be a digital display. In this circumstance, the display may be in communication with a processor and memory. The memory may store video files that can be depicted in the deck's display. In some circumstances, the video files include scenery files or other types of files. The display may also be in communication with a remote device that streams or downloads video files to the display. In some cases, the deck's display may be used to display information associated with the workout, with the user, with local news, with other types of information, or combinations thereof. In some examples, the treadmill's operational parameters can be presented in the display screen.

Any appropriate type of display may be incorporated into the deck. A non-exhaustive list of display types that may be used in accordance with the principles described in this disclosure, include cathode ray displays, liquid crystal displays, flat panel displays, stereo displays, plasma displays, electronically modulated optical displays, color display, monochrome displays, touch displays, electroluminescent panels, light emitting diodes displays, nano-emissive displays, quantum dot displays, digital light processing displays, active matrix displays, other types of displays, or combinations thereof.

The display screen may be made of any appropriate type of material that can withstand a user standing on it. This material may include Kevlar®, plastic, or another type of material. Further, the display screen may also be covered with a transparent coating that protects the screen from abrasion, dropped objects, or other types of contact.

In one embodiment, the display incorporated into the deck is located subjacent to at least a portion of the tread belt. In

this circumstance, the tread belt may be perforated or have other types of openings that allow the display to be visible through the tread belt. In another example, at least a portion of the tread belt is transparent and/or translucent, which allows the user to see at least a portion of the display when the tread belt rotates or when the tread belt is not moving with respect to the deck.

In some examples, the display is wider than the tread belt. In this example, a first portion of the display extends beyond the edge of the tread belt's first side and a second portion of the display extends beyond the edge of the tread belt's second side. In this example, portions of scenery or other information depicted with the deck's display can be visible on the exposed portions of the display on either side of the tread belt. In this situation, the tread belt surrounds just a portion of the display incorporated into the deck.

In some cases, the deck includes more than one display. A first display may be positioned adjacent to a first edge of the tread belt, and a second display may be positioned adjacent to a second edge of the tread belt. In this situation, the edges of the first and second deck displays terminate before reaching the tread belt. In other words, the tread belt may not overlap these first and second deck displays. These first and second deck displays may be aligned with the orientation of the deck. In other words, these displays may be situated lengthwise along the deck and/or aligned with the length of the tread belt. In some examples, at least one of the first and second deck displays span at least 10 percent of the deck's length, at least 20 percent of the deck's length, at least 30 percent of the deck's length, at least 40 percent of the deck's length, at least 50 percent of the deck's length, at least 60 percent of the deck's length, at least 70 percent of the deck's length, at least 80 percent of the deck's length, another percentage of the deck's length, or combinations thereof. In some examples, the deck includes at least one deck display, which is located on just one side of the deck.

The deck display may include a presentation side where the display presents content and is visible to the user. The deck display may also include a back side, which is facing downward and is not visible to the user when the treadmill is in operation. The tread belt includes an outer surface on which the user makes contact during the performance of an exercise, an inner surface which makes contact with the display and pulleys. The inner surface of the tread belt may surround the presentation side of the deck display and also surround the back side of the deck display.

In those situations where the tread belt includes perforations or other types of openings formed in the tread belt, the perforations may be defined in the outer surface and in the inner surface of the tread belt. The perforation may extend from the tread belt's outer surface to the tread belt's inner surface. Thus, the perforation may penetrate through the entire thickness of the tread belt. The perforations may be included along an edge of the tread belt, in the center of the tread belt, along a width of the tread belt, in patterns in the tread belt, arranged in another manner in the tread belt, or combinations thereof.

In other examples, the tread belt includes at least one window of transparent material. In some cases, the windows include a transparent material that fills the perforations so that the presentation side of the deck's display is visible. By incorporating the windows into the tread belt, the presentation side of the deck's display is protected from dirt, dust, or other types of particles that may reach the display through the perforations. In other examples, the tread belt is made of

a material where the entire tread belt is transparent. But, in other examples, just portions of the tread belt are transparent.

The presentation side of the display may have a low friction surface so that the tread belt may slide along the presentation side without a substantial drag. In those examples where the tread belt includes perforations or another type of openings defined in the tread belt, the perforations may include a perforation edge formed between a wall of the perforation and the inner surface of the tread belt. The perforation edge may be constructed to wipe away debris, dirt, dust, excess lubricant, or other substances that may obscure the view of the deck's display. In some cases, the perforation edge is shaped so that debris or other substances are caught by the perforation edge, which moves the debris or other substances along with the tread belt and off of the display. In some cases, the inner surface of the tread belt may be lined with a soft material that can collect dust or other types of particles. This lining may be a fabric, a soft material, or another type of material that can collect debris while having a low likelihood of scratching the display.

In examples where the tread belt is constructed to clean the display as the tread belt moves, any appropriate mechanism for cleaning the tread belt may be used. A wiper may be disposed adjacent to an exit side of the display that wipes off the debris or other substances collected in the perforations or the tread belt's inner surface. In other cases, a blower may direct a gas (e.g. air) over the regions of the tread belt's inner surface to remove the debris. In other cases, a chemical may be applied to the inner surface to clean the inner surface as the tread belt moves off of the display. In yet other examples, the inner surface of the tread belt may pass over a magnet to remove debris with magnetic properties from off of the tread belt's inner surface.

In some cases, a lubricant is applied between the inner surface of the tread belt and the presentation side of the display screen. In these situations, the lubricant may be a transparent lubricant that maintains the visibility of the display screen.

In yet another example, the deck may include multiple displays. In this type of example, a first deck display may be incorporated into the region of the deck's platform that is adjacent to a first edge of the tread belt, and a second deck display may be incorporated into the region of the deck's platform that is adjacent to a second edge of the tread belt. In examples with two deck display screens, the deck display screens may depict the same images or they may depict different images.

In examples where the console includes sensors that measure the user's physiological information, this measured information may be transmitted to the deck display through a wireless transmission protocol. In other examples, the display incorporated into the deck may be hardwired to the sensors located in the console.

The treadmill may also be in communication with a remote device over a network, such as the internet. The user may access the records of his or her exercise history, previous workouts, exercise recommendations, personal information, or combinations thereof. The remote device may record the workout information and/or the physiological information associated with the workout. An example of a user program that may be compatible with the principles described herein can be found at www.ifit.com, which is administered through Icon Health and Fitness, Inc. located

in Logan, Utah, U.S.A. In other cases, the remote device includes video files or other types of files with other types of information.

The information received from the remote device may be displayed in the console's display, in the deck's display, or combinations thereof. In some examples, all of the information is sent to both the console's display and to the deck's display. In this situation, both the displays in the console and the deck may show the same information. In other examples, the information from the remote device is separated into parts. In this situation, at least a portion of the information can be sent to the console's display and another portion of the information can be sent to the display in the deck. Under these circumstances, the console's display and the deck's display may present different information. Where the console display and the deck display present different information, some of the information depicted in each of the screens may overlap with each other.

In some embodiments, the treadmill simulates an outdoor trail on which the user is exercising. The console's display depicts the type of scenery that a runner would likely see if he or she were running on the simulated outdoor trail. This type of scenery may include the trail ahead of the user, the background scenery, landmarks in the distance, animals, vegetation, other types of scenery, the horizon, and combinations. In some cases, the deck's display screen may depict the exact same scenery as is depicted in the console's display. In some other examples, the deck's display may depict just a subset of the scenery, but not the same scenery as depicted in the console's display. For example, the scenery depicted in the deck's display may include just the scenery that is likely to be viewed by a user if the user were running on the simulated trail. In this example, the user may see the scenery from a top view in the deck's display whereas the user see the same scenery from a side view in the console's display. The top view of the scenery may include the trail, the vegetation around the trail, rocks, landmarks near the trail, just scenery that is close to the running path, other types of scenery, or combinations thereof.

In some circumstances, the console's display screen and the deck's display screen are coordinated. In this situation, the scenery from the console's display may flow to the deck's display as the user progresses along the simulated trail. For example, the console's display may depict a side view of a rock next to the running path, as the user progresses along the trail, the rock appears to get closer to the user. At some point along the user's progression, the side view of the rock transitions from the off of the console's display screen to the deck screen where the rock is seen from a top view. While this example describes an image of a rock transitioning from the console's display to the deck's display, images of any other appropriate type of scenery can transition from the console display to the deck display. In some case, the scenery in the deck's display is depicted from a side view as well.

For purposes of this disclosure, the term "coordinated" generally refers to the information depicted in the first display having a relationship with the information depicted in the second display. As illustrated above, the relationship between the information in the first display and the information in the second display is that at least some of the information from the first display transitions to the second display. In this situation, the overlapping information that was presented in the first display is also shown in the second display, but the presentation of the overlapping information in the second display is delayed in time. This is one example

11

of coordination between the first display and the second display. Further, coordinated display screens may include presenting the same information in both screens at the same time. In other examples, coordinated display screens may include causing the second display screen to be an extension of the first display screen.

In other examples, a relationship between the information depicted in the first and second display screens may be a relationship where the first display screen depicts an overview of a simulated course to be traveled by the user, and the second display depicts scenery of the simulated course. In this situation, the content depicted in the first and second displays convey information about the same course, although the type of content presented in the first and second displays are different.

A splitter may divide portions of a video feed (e.g. from a remote device or internal memory) to send some of the video data to the console's display while sending other data to the deck's display. In some cases, the splitter may cause the video data to be sent to each of the deck's display and the console's display at the same time. In other situations, the splitter may cause the separated video data to be sent to the deck display at a delayed time from the time that the splitter sends the video information to the console's display. In this case, some of the same scenery may be shown in both the console's display and the deck's display, but the scenery may be depicted in the deck's display at a later time than when it is depicted in the console's display. In yet other examples, the video feed to the console's display and the video feed to the deck's display may be separate and independent video feeds. In this example, the scenery or information depicted in the deck and console displays may be different. But, in other examples, the scenery depicted in the deck and console displays may depict the same simulated surroundings even though video feeds are from different, independent files.

While the examples above have been described with reference to a treadmill with a console display and a deck display, the treadmill may include a deck display without the console display. Further, while these principles have been described with respect to a treadmill, a display located below the movable element of the exercise device may be incorporated into other types of exercise machines.

For example, a display may be incorporated below the feet pedals in an elliptical trainer or a stationary bicycle. In these examples, the user has the advantage of having a display beneath him or her during the performance of the exercise thereby helping the user feel more like he or she is actually in a virtual setting. Further, the elliptical or stationary bike may present information to the user through a display located beneath his or her feet. In some examples, the top view images of a road or bicycle trail may be depicted in the displays located beneath, proximate, and/or subjacent to the foot pedals. In another example, the display may be incorporated into a rowing machine where the display is located beneath the slidable seat, the resistance mechanism, or another component of the rowing machine. In this example, the display may simulate ocean, river, and/or lake water as though the user were rowing on these bodies of water.

The deck displays, displays incorporated in the base of the elliptical trainer, displays located beneath resistance elements, displays located beneath pedals, displays located beneath rowing mechanisms, or other types of displays described above may include an ability to move. In some cases, these displays may incline, decline, rotate, twist, tilt from side to side, or otherwise move. In some cases,

12

these displays move in response to events occurring in the simulated workout. For example, the displays may incline as the user is simulated to travel up steep a portion of an outdoor trail. In cases where the display is a deck display in a treadmill, the deck displays may move with the deck. But in some cases, the deck display may move independent of the deck.

The coordinating system may include a combination of hardware and programmed instructions for executing the functions of the coordinating system. The coordinating system may include processing resources that are in communication with memory resources. Processing resources include at least one processor and other resources used to process the programmed instructions. As described herein, the memory resources may represent generally any memory capable of storing data such as programmed instructions or data structures used by the coordinating system.

The processing resources may include I/O resources that are capable of being in communication with a remote device that stores the user information, eating history, workout history, external resources, databases, or combinations thereof. The remote device may be a mobile device, a cloud based device, a computing device, another type of device, or combinations thereof. In some examples, the system communicates with the remote device through a mobile device which relays communications between the coordinating system and the remote device. In other examples, the mobile device has access to information about the user. The remote device may collect information about the user throughout the day, such as tracking calories, exercise, activity level, sleep, other types of information, or combination thereof.

The remote device may execute a program that can provide useful information to the coordinating system. An example of a program that may be compatible with the principles described herein includes the iFit program which is available through www.ifit.com identified above. An example of a program that may be compatible with the principles described in this disclosure is described in U.S. Pat. No. 7,980,996 issued to Paul Hickman. U.S. Pat. No. 7,980,996 is herein incorporated by reference for all that it discloses. In some examples, the user information accessible through the remote device includes the user's age, gender, body composition, height, weight, health conditions, other types of information, or combinations thereof.

The processing resources, memory resources, and remote devices may communicate over any appropriate network and/or protocol through the input/output resources. In some examples, the input/output resources includes a transmitter, a receiver, a transceiver, or another communication device for wired and/or wireless communications. For example, these devices may be capable of communicating using the ZigBee protocol, Z-Wave protocol, BlueTooth protocol, Wi-Fi protocol, Global System for Mobile Communications (GSM) standard, another standard, or combinations thereof. In other examples, the user can directly input some information into the tracking system through a digital input/output mechanism, a mechanical input/output mechanism, another type of mechanism, or combinations thereof.

The memory resources may include a computer readable storage medium that contains computer readable program code to cause tasks to be executed by the processing resources. The computer readable storage medium may be a tangible and/or non-transitory storage medium. The computer readable storage medium may be any appropriate storage medium that is not a transmission storage medium. A non-exhaustive list of computer readable storage medium types includes non-volatile memory, volatile memory, ran-

13

dom access memory, write only memory, flash memory, electrically erasable program read only memory, magnetic based memory, other types of memory, or combinations thereof.

The memory resources may include a first display timer that represents programmed instructions that, when executed, cause the processing resources to control the timing of the content presented in the first display. Also, the memory resources may include a second display timer that represents programmed instructions that, when executed, cause the processing resources to control the timing of the content presented in the second display.

In some cases, the video content for both the first and second displays is from the same video file. The content in the video file may contain timing markers that can be used to coordinate the presentation of the content in the first and second displays. In those examples where the first and second displays present the same content at the same pace, the timing markers can be synchronized to be displayed at the same time. In those examples, where the content is to be presented in the first display and then presented in the second display a short time later, the second display can be instructed to present the content so that the timing markers are delayed from presentation in the second display by a predetermined time amount from when the corresponding timing markers are displayed in the first display.

In some examples, a portion of the content from the video file is directed to the first display for presentation and another portion of the content is directed towards the second display for presentation with the assistance of a video splitter. In this example, the timing markers can be coordinated so that the content in the first and second displays are presented at the appropriate time in relation to each other.

Further, the memory resources may be part of an installation package. In response to installing the installation package, the programmed instructions of the memory resources may be downloaded from the installation package's source, such as a portable medium, a server, a remote network location, another location, or combinations thereof. Portable memory media that are compatible with the principles described herein include DVDs, CDs, flash memory, portable disks, magnetic disks, optical disks, other forms of portable memory, or combinations thereof. In other examples, the program instructions are already installed. Here, the memory resources can include integrated memory such as a hard drive, a solid state hard drive, or the like.

In some examples, the processing resources and the memory resources are located within the exercise device, the first display, the second display, an external device, another type of device, or combinations thereof. The memory resources may be part of any of these device's main memory, caches, registers, non-volatile memory, or elsewhere in their memory hierarchy. Alternatively, the memory resources may be in communication with the processing resources over a network. Further, data structures, such as libraries or databases containing user and/or workout information, may be accessed from a remote location over a network connection while the programmed instructions are located locally. Thus, the coordinating system may be implemented with the exercise device, a mobile device, a wearable computing device, a head mounted device, a server, a collection of servers, a networked device, a watch, or combinations thereof.

In some examples, the treadmill includes a console display that has an inwardly curved screen. In these examples, the scenery depicted in the console display can create a more realistic feel that the user is in the simulated environment.

14

Further, the treadmill may include a slatted running track incorporated into the deck. In some examples, the slatted running track is used in lieu of a tread belt. Also, in this type of example, at least some of the track's slats are supported with a rigid member that extends from a first track formed in a first side wall of deck's platform to a second track formed in a second side wall of deck's platform. The slats may be flexibly coupled to each other. In one specific example, the slats can be joined with a hinge joint.

In some cases, the slatted running track is driven by a motor. In other examples, the slatted running track is self-powered by the user. In instances where the slatted running track is self-powered, the slatted running track may be connected to a flywheel to maintain the track's inertia as the user runs.

In some cases, the treadmill includes a console screen with multiple displays. A first display in the console screen may depict scenery, a top view of an exercise course, a physiological parameter of the user, an operating parameter of the treadmill (e.g. speed, incline, side tilt angle, user temperature, climate temperature, time of day, distance traveled, another parameter, local news, entertainment, or combinations thereof). In these types of example, the other displays may each depict different content or similar content to the first display. In some instances, the user may select which content is depicted in which display. For instance, if the largest display is the first display, the user may select the content from one of the other displays to be depicted in the first display. In one particular example, at least some of the content in one of the other displays may be coordinated with the content in the first display or one of the other displays.

What is claimed is:

1. An exercise device comprising:
a frame;
an upright portion of the frame;
a first display connected to the upright portion of the frame;
an exercise deck included in the frame, the exercise deck including:
a first pulley connected to a front portion of the exercise deck,
a second pulley connected to a rear portion of the exercise deck,
a second display incorporated into the exercise deck, and
a tread belt surrounding the first pulley and the second pulley, surrounding at least a portion of the second display, and movable in a performance of an exercise, a first portion of the second display extending beyond a first edge of a first side of the tread belt and a second portion of the second display extending beyond a second edge of a second side of the tread belt; and
a video splitter device configured to divide a video feed into a first video feed and a second video feed, and configured to output the first video feed to the first display and the second video feed to the second display.

2. The exercise device of claim 1, wherein the first video feed contains some overlapping data that overlaps with the second video feed and some non-overlapping data that does not overlap with the second video feed, and the overlapping data is delayed from presentation in the second display from when the overlapping data is displayed in the first display.

3. The exercise device of claim 2, wherein the overlapping data depicts scenery and wherein the delaying causes an effect of having the scenery appear to transfer from the first display to the second display.

15

4. The exercise device of claim 1, wherein the second display is adjacent to at least a portion of the tread belt.
5. The exercise device of claim 1, wherein the second display is below at least a portion of the tread belt.
6. The exercise device of claim 1, wherein the first display and the second display are configured to depict coordinated images.
7. The exercise device of claim 1, wherein the first video feed and the second video feed are identical.
8. The exercise device of claim 1, wherein the first video feed contains at least some data that does not overlap with data in the second video feed. 10
9. The exercise device of claim 1, wherein the second display is covered with a transparent plastic film.
10. An exercise device comprising: 15
an upright structure;
a first display connected to the upright structure; and
an exercise deck connected to the upright structure, the
exercise deck including:
a first pulley connected to a front portion of the exercise 20
deck,
a second pulley connected to a rear portion of the
exercise deck,
a tread belt surrounding the first pulley and the second
pulley, and
a second display is incorporated into the exercise deck 25
and is adjacent to or below a portion of the tread belt,
a first portion of the second display extending
beyond a first edge of a first side of the tread belt and
a second portion of the second display extending
beyond a second edge of a second side of the tread
belt;
wherein the first display and the second display are 30
configured to depict coordinated images.
11. The exercise device of claim 10, further including a 35
video splitter device configured to divide a video feed into
a first video feed and a second video feed, and configured to
output the first video feed to the first display and the second
video feed to the second display.
12. The exercise device of claim 11, wherein the first 40
video feed contains some overlapping data that overlaps
with the second video feed and some non-overlapping data
that does not overlap with the second video feed, and the
overlapping data is delayed from presentation in the second
display from when the overlapping data is displayed in the
first display.
13. The exercise device of claim 12, wherein the over- 45
lapping data depicts scenery and wherein the delaying

16

- causes an effect of having the scenery appear to transfer from the first display to the second display.
14. The exercise device of claim 11, wherein the first video feed and the second video feed are identical.
  15. The exercise device of claim 10, wherein the second display is covered with a transparent plastic film.
  16. An exercise device comprising:
an upright structure;
a first display connected to the upright structure; and
an exercise deck connected to the upright structure, the
exercise deck including:
a first pulley connected to a front portion of the exercise 20
deck,
a second pulley connected to a rear portion of the
exercise deck,
a tread belt surrounding the first pulley and the second
pulley,
a second display incorporated into the exercise deck
and surrounded by at least a portion of the tread belt,
and
a video splitter device configured to divide a video feed
into a first video feed and a second video feed, and
configured to output the first video feed to the first
display and the second video feed to the second
display;
  17. The exercise device of claim 16, wherein a first
portion of the second display extends beyond a first edge of
a first side of the tread belt and a second portion of the
second display extends beyond a second edge of a second
side of the tread belt.
  18. The exercise device of claim 16, wherein the second
display is covered with a transparent plastic film.
